[57] **CLAIM**

The ornamental design for a liquid test meter, as shown and described.

DESCRIPTION

FIG. 1 is a perspective view of a liquid test meter showing my new design;

FIG. 2 is a front elevational view thereof;

FIG. 3 is a right hand side elevational view thereof;

FIG. 4 is a bottom plan view thereof;

FIG. 5 is a top plan view thereof;

FIG. 6 is a rear elevational view thereof; and,

FIG. 7 is a left hand side elevational view thereof.

The broken line showing of an electrode and connecting cable are for illustrative purposes only and forms no part of the claimed design.
